UNITED STATES PATENT OFFICE.

ADELE M. KAUFFMAN, OF ST. PAUL, MINNESOTA.

DESIGN FOR AN ABDOMINAL BAND.

SPECIFICATION forming part of Design No. 33,320, dated October 2, 1900.

Application filed March 2, 1900. Serial No. 7,133. Term of patent 3½ years.

To all whom it may concern:

Be it known that I, ADELE M. KAUFFMAN, citizen of the United States, residing at St. Paul, in the county of Ramsey and State of Minnesota, have invented and produced a new and original Design for Abdominal Bands, of which the following is a specification, reference being had to the accompanying drawings, forming part thereof.

Figure 1 is a rear view of an abdominal band, illustrating my new design; and Fig. 2 is a side elevation of Fig. 1.

As shown in the drawings, the leading or material feature of my design is the shape of the garment as an entirety. The band A is circular in shape and wider in front than in the rear. Its lower edge is contracted, being smaller than the body of the band, and carries at its sides, on its lower edge, depending

legs B and C, which are short and cut away between, leaving a transverse opening, extending from the front to the rear, between the band and legs. Each leg has its lower edge contracted, and its upper edge on one side extends upward to the band.

Having described my invention, what I claim as new, and desire to protect by Letters Patent, is—

The design for an abdominal band, as herein shown and described.

In testimony whereof I have signed my name to this specification in the presence of two subscribing witnesses.

ADELE M. KAUFFMAN.
